UNITED STATES PATENT OFFICE.

WILLIAM C. OWEN, OF CLEVELAND, OHIO.

DESIGN FOR A TIRE-CASING.

52,170.

Specification for Design.

Patented July 9, 1918.

Application filed December 26, 1917. Serial No. 208,996. Term of patent 7 years.

To all whom it may concern:

Be it known that I, WILLIAM C. OWEN, a citizen of the United States, residing at Cleveland, in the county of Cuyahoga and State of Ohio, have invented a new, original, and ornamental Design for Tire-Casings, of which the following is a specification, reference being had to the accompanying drawing, forming a part thereof.

Figure 1 is a plan view of a portion of a

tire-casing showing my new design and Fig. 2 is a sectional view of same on the line 2—2 of Fig. 1.

I claim—

The ornamental design for a tire-casing, as shown.

WILLIAM C. OWEN.

Witnesses:

JOHN A. BOMMHARDT,
G. W. ROSENBERG.
